J. D. Elliott,
Dressing Staves.
No 10,227. Patented Nov 15, 1853.

UNITED STATES PATENT OFFICE.

JOSEPH D. ELLIOT, OF LEICESTER, MASSACHUSETTS.

MACHINE FOR DRESSING STAVES.

Specification of Letters Patent No. 10,227, dated November 15, 1853.

To all whom it may concern:

Be it known that I, JOSEPH D. ELLIOT, of 5
Leicester, in the county of Worcester and
State of Massachusetts, have invented cer-
tain new and useful Improvements in Ma-
chines for Dressing Staves; and I do hereby
declare the following to be a full, clear, and
exact description of the same, reference be-
ing had to the accompanying drawings,
10 making a part thereof, in which—

Figure 1, represents a perspective view
of the machine. Fig. 2, represents a trans-
verse section through the bed.

The nature of my invention relates more
15 particularly to the use of a transversely
inclined bed upon which the staves are fed
into the cutters, so as to adapt the machine
to the dressing, of thick or thin, tapering
or wedge shaped, riven staves, with the
20 grain of the wood, without separately ad-
justing the machine, or assorting of the
staves.

To enable others skilled in the art to make
and use my invention, I will proceed to de-
25 scribe the same with reference to the draw-
ings.

The general construction of the machine
is similar to that which I have recently
withdrawn from the Patent Office, the dis-
30 tinguishing difference being in the bed.

A, represents the table or bench, to which
a standard B, is attached. From said stand-
ard B, projects over the table an arm C,
for supporting in an inclined position the
35 shaft D, carrying the cutter wheel E, at
its lower end, and a drum or pulley F, at
its upper end, for a belt, by which it may be
driven. This cutter wheel E dresses the
concave side of the stave, and may be made
40 adjustable through its shaft. A weighted
roller G, is placed as near to the cutting line
of the wheel E, as may be, the wheel itself
being hung on an inclined shaft for this
purpose, to hold the stave against the bed
45 H, and against the lifting cut of the wheel.
This roller may be weighted, hung upon
springs, or may possess the requisite weight
within itself for holding down the stave.

Underneath the bed is a concave cylinder

I, having straight knives arranged trans- 50
versely across it, which knives dress the
convex side of the stave. The bolt or stave
is held against the action of the under cut-
ter by a swiveled weighted roller J, on top
of the table, which roller may be held down 55
by weights, springs &c., in the well known
manner.

K, is a transversely inclined or slightly
concave bed, which may have its surface
slightly grooved or roughened, so that the 60
stave shall not slip to one side or the other
of the bed, after it has been properly placed
thereon—the swiveled roller J, aiding to
hold it (the stave) firmly against the bed.

The staves are fed in between the guide 65
pieces L, by means of an endless chain of
dogs or bars, which being common and well
known need not be shown. Or other posi-
tive feed motion may be used if found essen-
tial. 70

It is well known that staves are riven
from the bolts in radial lines drawn from
the center to the circumference of the bolt,
or log, and that the stave when undressed
is consequently thicker at one edge than the 75
other. They may also taper in the direction
of their length, and be winding from end
to end. By machines heretofore constructed
for dressing such riven staves, the staves
had to be assorted into sizes and the cutters 80
adjusted for each varying size. In my ma-
chine, if the stave be thick it is fed in on the
side a, of the bed. If thin on the side b of
the bed. If thick at one end and thin at the
other, it is skewed on the bed so that the 85
thick part shall pass through at a, and the
thin part at b, thus adapting the machine to
staves of any form as they come in bulk;
dressing them with the grain; and by this
arrangement of inclined bed, and swiveled 90
roller, which must adapt itself to the vari-
ous shapes or forms of the staves, and the
manner of feeding them in, I can take a full
shaving from convex or outside of the
stave, while the deficiency of wood will be 95
on the inside of the barrel when made up,
and the grain of the wood is not cut across,
which would allow the barrels to leak.

Having thus fully described the nature of my invention, what I claim therein as new, and desire to secure by Letters Patent, is—

The combination of the transversely inclined bed with the swiveled roller, for the purpose of adapting the machine to the dressing of riven staves with the grain of the wood, whether thick or thin, tapering,

or inclined, from edge to edge, without any separate adjustment for the various sizes, substantially as described.

J. D. ELLIOT.
